UNITED STATES PATENT OFFICE.

WILLIAM H. CATER, OF CHICAGO, ILLINOIS.

WELL SCREEN.

Application filed October 18, 1920. Serial No. 417,699.

To all whom it may concern:

Be it known that I, WILLIAM H. CATER, a citizen of the United States, residing at Chicago, in the county of Cook and State of Illinois, have invented certain new and useful Improvements in Well Screens, of which the following is a specification.

My invention concerns an important and valuable improvement or modification in the usual construction of well casings or linings which are forced or fed downwardly in the ground step by step as the sinking of the well progresses, the invention relating more particularly or especially to structural and functional improvements in the sharp-edged flaring foot or bell-shaped shoe with which the lower end of the metal casing is fitted.

In the sinking of a well in which such a lining or casing is used, the latter is loaded or weighted, as by a box or receptacle charged with stones or other heavy bodies resting on its top, or otherwise, to facilitate its descent, the lower end of the casing having a flaring, apertured or foraminated, sharp-edged base or foot on which the weight of the casing and its load is imposed. As will be readily understood, such bell-shaped foot or shoe is driven or sunk into the ground by the weight referred to, such action being aided by its thin front or bottom cutting edge.

A pump suspended on the lower end of a cable or chain is lowered in such casing, and when it rests on the ground at the lower end of the well opening and within such base or shoe, it is manipulated by the cable or chain to create a high degree of suction resulting in the pump being automatically filled with water and earth, a part of which flows into the casing through the apertures of such bell foot and around the lower edge of the latter, the remainder being sucked into the pump from the ground surrounded by the bell and on which the pump rests. Such sudden removal of a charge of earth beneath the casing by reason of the suction created and the weight of the casing itself and the load on its upper end causes the shell or casing to descend a substantial amount.

The pump, which is filled with dirt, gravel, and water, of which a material percentage is solid matter, is lifted out of the casing by the cable or chain referred to and its contents discharged or dumped on the ground

to one side of the mouth of the well, whereupon the pump is again lowered into the well and the operation repeated. In this way the depth of the well is increased intermittently and progressively.

Obviously, the descent of the sheet-metal casing with its relatively large area of frictional contact with the outside or surrounding earth is an important factor in the production of such wells and difficulty has heretofore been experienced in causing such downward travel with proper facility.

I have, however, discovered a very simple means to overcome this detriment and obstacle to the wholly satisfactory operation of the appliance and to assist the casing and its shoe in its intermittent or periodical downward movements. The means necessary to produce the desired results is extremely simple, its desirability and the effectiveness of its action having apparently escaped the notice and attention of those skilled in this art and acquainted with these structures and their modes of operation.

It will be recalled that the strong suction of the pump dislodges and carries away a substantial amount of earth from the lower end of the well and, due to such removal, the shell or casing is free to descend by gravity, but such movement is opposed by the relatively large amount of friction of the earth pressing against its outer face, whereby such downward travel of the casing is dependent in large measure upon the weight imposed thereon to force it down. The leading object of my invention is to employ the suction action of the pump itself to directly assist in pressing the casing down, and to employ the weight of the earth resting on the outwardly flaring surface of the shoe to assist in this action. As stated, the suction of the pump is exerted at the lower end of the latter while it is at the bottom of the well, and my invention aims to take advantage of this great pressure to assist in loosening and pulling away the earth directly beneath the edge of the casing foot or shoe and to employ the suction action specified to also assist in drawing down the casing. To this end, instead of employing a perforated or apertured flaring base or shoe, through the holes of which water may flow inwardly during the occurrence of the suction action, I use an unperforated or unapertured base or foot for the casing whereby

the suction action is not at least in part negated or neutralized by the water flowing through the holes of the foot or base, but on the contrary by employing the unperforated, 5 bell-shaped shoe, suction is exerted more effectively to draw the earth from beneath the edge of the shoe or foot, and because such hydraulic action is brought into operation around the lower edge of the shoe, the 10 external downward pressure both of the earth and water on the flaring outer surface of the shoe aids the pushing of the latter down as is required to secure facility and effectiveness in the descent of this member. 15 This beneficial and advantageous action occurs regardless of whether the casing member is apertured or reticulated so long as the foot or shoe is unperforated because the great suction occurs within the latter. 20 To enable those skilled in this art to have a full and complete understanding of this invention and the various advantages accruing from its use, in the accompanying drawing, forming a part of this specification and to 25 which reference should be had in connection with the following detailed description, I have illustrated a preferred and desirable embodiment of the invention, like reference characters referring to the same parts throughout the several views.

In this drawing:

Figure 1 is a vertical central section through the well-casing and its shoe and the enclosed pump;

35 Figure 2 is a horizontal section on line 2-2 of Figure 1 on a reduced scale; and

Figure 3 is a horizontal section on line 3-3 of Figure 1.

Referring to these drawings, the perforated or reticulated sheet-metal casing or lining 10 for the well is built up of a series of abutting cylindrical sections fastened together endwise in any approved manner, each portion having, if desired, although 45 they are not essential, a plurality of apertured slits formed preferably by deforming outwardly small sections or strips of the metal leaving slits or slots between them and the main body of the casing. Such cylindrical shell at its lower end fits in and is fastened to the top portion of a downwardly widening or upwardly converging cast-metal foot or shoe 11 of a shape approximating the frustum of a cone, such member conveniently being composed of a plurality of 50 longitudinal sections 12, 13, and 14 bolted together at 15, 15 and having a relatively sharp lower edge whereby it may more readily penetrate the earth. The weight or 55 load imposed on the upper end of such shell or lining is not shown.

60 The pump referred to comprises a cylinder 17 which at its lower end fits over and is secured to a base ring 18 the bottom edge of 65 which is notched or recessed at 19, 19 for the

passage inwardly therethrough of water, earth, gravel, etc. Such end element 18 within the lower part of the cylinder 17 is equipped with a hinged valve 20 disposed in an inclined relation, when closed over the 70 end of member 18, to facilitate its upward opening movement under the suction action to which it is subjected.

Internally the pump cylinder accommodates a reciprocating perforated piston or 75 plunger 21 mounted fixedly on the lower end of a vertical rod or shaft 22 having an eye 23 at its upper end for the attachment of an operating cable or chain not shown. A round flexible valve 24, such as leather or rubber, 80 is positioned over the top face of the plunger and is adapted to open and close the holes of the latter depending upon the direction of movement of the parts as will be readily understood. A coil cushion spring 25 surrounds the rod or shaft just above such valve. 85

At the top end of the pump, rod or shaft 22 slides through a bearing-block 26 swivelled at 27, 27 in the walls of the pump cylinder, the latter being cut away on one side at 28 90 for the sidewise discharge of the pump's contents, during which operation the rod or shaft 22, by reason of the turning of the bearing-block, occupies a recess 29 cut in the opposite side of the pump cylinder. 95

The operation of this appliance occurs practically as follows: Assuming that the casing or lining 10 and the shoe or foot 11 have been weighted or loaded at the top end of the former, the pump is lowered in 100 the well and the casing until the base ring 18 rests on the earth at the bottom of the well, in which position it will be surrounded by the element 11, the piston or plunger 21 being lowered to the bottom portion of the 105 pump shell or cylinder 17, the valve 20 at this time being closed. Then the cable or chain engaging the eye 23 is lifted causing the rapid ascent of the piston or plunger which creates a high degree of suction beneath it, such unbalancing of pressures occasioning the opening of valve 20 and the filling of the pump cylinder beneath the piston with a mixture of dirt, gravel, water, etc. Owing to the fact that such substantial suction is created by the pump in the unapertured or unperforated sloping gravity foot or shoe, it is particularly effective, because the shoe or foot is without holes or inlet, in removing earth from beneath the foot or shoe, 110 and in sucking or drawing the latter downwardly, which action, of course, is assisted by gravity through the earth pressing down on the sloping outer face of the shoe. If the bell-shaped foot were apertured, the water in 115 flowing inwardly through such perforations would tend to draw the surrounding earth inwardly in the same direction, which action would render no assistance in the necessary and essential downward travel of the 120 earth. 125

casing. Where, however, an unapertured foot or shoe is employed, the outside earth tends to be drawn or sucked downwardly on the sloping surface of the shoe by reason of the suction action present around its bottom edge and such tendency to downward movement by reason of the suction is supplemented by the action of gravity on such earth which effectively and efficiently assists 5 in forcing the casing or lining downwardly. Thus it will be seen that a marked and distinct advantage is had in employing an unperforated foot or shoe and it is in the use of 10 such a member that the present invention 15 resides.

Those skilled in this art will understand that the invention is not necessarily limited and restricted to the precise and exact embodiment shown and described since such 20 structure may be changed more or less in mechanical details without departure from the substance and essence of the invention and without the sacrifice of any of its substantial benefits and advantages.

25 I claim:

1. As an article of manufacture, the combination of a sheet-metal casing adapted to line a well composed of sections of substantially-uniform diameter throughout their individual lengths united together endwise by external couplings, and an unperforated foot flaring outwardly downwardly both externally and internally in approximately the same degree and secured to the lower end 30 of said casing, said foot having a lower relatively-sharp earth-cutting edge of materially greater diameter than the external diameter of said couplings joining together the sections of the casing.

40 2. As an article of manufacture, the combination of a sheet-metal casing adapted to line a well composed of sections of substantially-uniform diameter throughout their individual lengths united together endwise by external couplings, and an unperforated 45 downwardly outwardly flaring foot secured to the lower end of said casing, said foot having a lower relatively-sharp earth-cutting edge of materially greater diameter than the external diameter of the couplings joining together the sections of the casing, the outer face of said foot at said edge being practically cylindrical, the inner face of said foot at said edge being substantially conical.

55 3. As an article of manufacture, the combination of a sheet-metal casing adapted to line a well composed of sections of substantially-uniform diameter throughout their individual lengths united together endwise by external couplings, and an unperforated 60 foot flaring outwardly downwardly both externally and internally in approximately the same degree and secured to the lower end of the casing, said foot having a lower relatively-sharp earth-cutting edge of materially

greater diameter than the external diameter of the couplings joining together the sections of the casing, the outer face of said foot at said edge being practically cylindrical, the inner face of said foot at said edge being 70 substantially conical.

4. As an article of manufacture, the combination of an apertured sheet-metal casing adapted to line a well composed of sections of substantially-uniform diameter throughout their individual lengths united together endwise by external couplings and an unperforated foot composed of a plurality of sections secured together lengthwise the foot and fastened to the lower end of the sheet- 75 metal well casing, said foot flaring outwardly downwardly both externally and internally in approximately the same degree and having a lower relatively-sharp earth-cutting edge of materially greater diameter 80 than the external diameter of the couplings joining together the sections of the casing, the outer face of said foot at said edge being practically cylindrical, the inner face of said foot at said edge being substantially 85 conical.

5. As an article of manufacture, a cast-metal, unperforated foot with a lower relatively-sharp edge, composed of a plurality of sections secured together lengthwise the foot 90 and adapted for application to the lower end of a sheet-metal well-casing, the outer face of said foot at said edge being practically cylindrical, the inner face of said foot at said edge being substantially conical.

6. As an article of manufacture, a cast-metal unperforated foot with a lower relatively-sharp edge composed of a plurality of sections secured together lengthwise the foot 95 and adapted for application to the lower end of a sheet-metal well-casing, said foot flaring outwardly downwardly both externally and internally in approximately the same degree, the outer face of said foot being practically cylindrical at said edge, the inner face of said foot at said edge being substantially conical.

7. In an appliance for sinking wells, the combination of a sheet-metal casing adapted to line said well composed of sections of substantially uniform diameter throughout their individual lengths united together endwise by external couplings, an unperforated foot flaring outwardly downwardly both externally and internally in approximately the same degree and secured to the lower end of said casing, said foot having a lower relatively-sharp earth-cutting edge of materially greater diameter than the external diameter of said couplings joining together the sections of the casing, and a pump to create a suction in said foot for the removal of earth and the sinking of the well, whereby the creation of such suction in the unperforated foot by unbalancing the pressures on the op- 115 120 125 130

posite sides of the foot assists in the descent of the casing and foot.

8. In an appliance for sinking wells, the combination of a sheet-metal casing adapted to line a well composed of sections of substantially uniform diameter throughout their individual lengths united together endwise by external couplings, an unperforated downwardly outwardly flaring foot secured to the lower end of said casing, said foot having a lower relatively-sharp earth-cutting edge of materially greater diameter

than the external diameter of the couplings joining together the sections of the casing, the outer face of said foot at said edge being 15 practically cylindrical, the inner face of said foot at said edge being substantially conical, and a pump to create a suction in said foot for the removal of earth and sinking of the well, whereby the creation of such suction 20 in the unperforated foot by unbalancing the pressures on the opposite sides of the foot assists in the descent of the casing and foot.

WILLIAM H. CATER.
